United States Patent [19]

Takekoshi et al.

[11] Patent Number: Des. 317,596

[45] Date of Patent: ** Jun. 18, 1991

[54] OPERATOR CONSOLE FOR MAGNETIC RESONANCE IMAGING SYSTEM

[75] Inventors: Isamu Takekoshi; Mitsuhiro Onuma, both of Tokyo; Kazuki Torai, Kokubunji; Kazunori Hashimoto, Tachikawa; Toshiaki Aritomi, Katsuta, all of Japan

[73] Assignee: Hitachi, Ltd., Tokyo, Japan

[**] Term: 14 Years

[21] Appl. No.: 389,566

[22] Filed: Aug. 4, 1989

[30] Foreign Application Priority Data

Mar. 20, 1989 [JP] Japan 1-9800

[57] CLAIM

The ornamental design for an operator console for magnetic resonance imaging system, as shown and described.

DESCRIPTION

FIG. 1 is a front, top and right side perspective view of an operator console for magnetic resonance imaging system showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and

FIG. 7 is a bottom plan view thereof;

FIG. 8 is a front, top and right side perspective view thereof with two protective covers shown in the opened condition and further a display is shown in broken lines for illustrative purposes only and forms no part of the claimed design.

*FIG. 1**FIG. 2*FIG. 3

FIG. 4

FIG. 5

FIG. 6

FIG. 7

FIG. 8
